UNITED STATES PATENT OFFICE.

CHARLES ZALLUD, OF NEW YORK, N. Y., ASSIGNOR OF ONE-HALF TO ISAAC PFORZHEIMER, OF SAME PLACE.

CHECK-RECORDING MACHINE.

SPECIFICATION forming part of Letters Patent No. 432,961, dated July 22, 1890.

Application filed October 31, 1889. Serial No. 328,843. (No model.)

To all whom it may concern:

Be it known that I, CHARLES ZALLUD, of the city, county, and State of New York, have invented a certain new and useful Improvement 5 in Check-Recording Machines, of which the following is a specification.

My improvement relates to machines adapted to receive checks denoting the value of purchases made, and to record the value of 10 such checks.

I will describe in detail my improvement, and then point out the novel features in claims.

In the accompanying drawings, Figure 1 is 15 a vertical section taken on the line 1 1, Fig. 3. Fig. 2 is a vertical section taken on the line 2 2, Fig. 1, and looking in the direction of the arrow, Fig. 1. Fig. 3 is a horizontal section taken on the line 3 3, Fig. 2. Fig. 4 20 is a face view of a certain check which may be employed.

Similar letters of reference designate corresponding parts in all the figures.

In carrying my improvement into effect I 25 use checks upon which are raised figures denoting a certain value. One of these checks having been passed into the machine, an impression of the figures denoting the value of the check is taken upon a traveling strip of 30 paper. At the close of the day's business or at such other time as it may be deemed necessary the strip of paper having the figures denoting the value of the checks imprinted upon it is removed from the machine and the 35 imprints are footed up. The total of such imprint must equal the total of the checks passed into the machine and the total of cash received for which checks have been used.

The machine is contained in a case A, which 40 case is surmounted by a casing A', provided with a chute A². The checks are to be passed down this chute. Preferably the sides of the casing A' will be fitted with glass plates a. The checks employed in the machine are to 45 have the figures denoting their value arranged upon both sides. The cashier upon one side and the customer upon the other may then, by looking through the glass plates upon the sides of the casing A', both see the value of 50 the check which has been passed down the

chute. Preferably, also, the checks, as shown more clearly in Fig. 1, will have the figures arranged upon both ends, but extending in reverse directions to each other, so that whichever way a check is dropped into the machine 55 certain of the figures will be brought into proper position for printing, as will be hereinafter more clearly described. The check, having been passed through the chute A², rests at its lower edge upon a rigid stop a', 60 constituting in this instance part of a portion A³ of the frame of the machine. When in this position, it will be observed that one portion of the check, or, say, about one half ($\frac{1}{2}$) thereof, is within the case A, while the other 65 half is above the same and within the casing A'. It is the portion within the casing A' which may be seen by the cashier and customer, as previously described.

The figures upon the check constitute in 70 effect type, and from these type an impression is to be taken. Such impression is taken upon a traveling strip of paper B, which strip of paper passes at one side of the portion of the check which is within the case A.

I have shown a convenient means for inking the type upon the check, so that an impression may be taken upon the strip, consisting of an inking-ribbon B', which also passes at one side of the check and between 80 the check and the traveling strip of paper. If, now, the inking-ribbon and the traveling strip of paper be together pressed against the type upon the check which are opposite, an impression of such type will be taken upon 85 the strip of paper.

I have shown means for causing the inking-ribbon and the strip of paper to be thus pressed against the type, consisting of a plunger C, which plunger is adapted to be 90 moved to and fro in a guideway c, formed upon the portion A³ of the frame. The plunger C constitutes in effect a platen. The plunger C in this instance is made up of two sections c' c². The section c² is arranged 95 within a recess c³, formed within the section c', the outer extremity of which section c² is provided with a head c⁴. The recess c³ is shouldered near its rear end, as shown more clearly in Fig. 2. Between the head c⁴ and 100

said shoulder is arranged a coil-spring c^4 , the tendency of which is to always force the section c^2 outwardly. Beyond said shoulder the recess c^3 is diminished, and the shank c^5 of the 5 section c^2 extends into said diminished portion. A pin c^6 , extending from the inner side of the diminished portion of the recess c^3 and into a longitudinally-extending slot c^7 , formed in the shank of the section c^2 , prevents a too- 10 extended movement of said section in either direction. This construction is advantageous, because it provides means whereby the plunger will act with a yielding pressure against the type, and will thus prevent the 15 type from being battered, as it might otherwise be during the rapid working of the machine. Longitudinal movement is imparted to the plunger C by means of a cam D, which cam is rigidly mounted upon a vertically-extending 20 rock-shaft D', which rock-shaft is journaled near its lower end in the base of the machine and near its upper end in a bracket d, extending from the portion A³ of the frame of the machine.

25 Mounted in the outer portion of the plunger C are two rollers d' d². When the shaft D' is rocked in one direction, the cam D will act upon the roller d' to force the plunger inwardly to cause an impression to be taken 30 from the check. When, however, the shaft is rotated in the other direction, the cam will operate upon the roller d² to move the plunger outwardly and away from the check.

A rocking motion is imparted to the shaft 35 D' by means of a handle D², extending to the exterior of the case A through a slot d³, formed horizontally in the case. The inner end of the handle D² is secured to the shaft D'. By moving the handle through the slot 40 d³ the operation just described is effected. At the ends of the slot d³ are elastic stops d⁴, preferably of india-rubber, against which the handle will strike when moved. These stops prevent undue jarring and noise.

45 Surrounding the shaft D', near its lower extremity, is a coil-spring d⁵. This coil-spring has one end bearing against the handle D² and the other against a pin d⁶, extending upwardly from the base of the machine. The 50 tendency of this spring is always to force the handle D² into a normal position, or, in other words, into such position as to rock the shaft D' to cause the plunger to be withdrawn.

The operation of printing from the check 55 is the first that takes place after the check has been deposited in the machine, and this operation is effected by moving the handle D² in the direction of the arrow, Fig. 3. By the reverse movement of the handle the strip 60 of paper is caused to be fed forward, so as to bring a fresh portion thereof into position to be printed upon, and the check from which an impression has just been taken is moved out of the way to make room for another 65 check, which may be dropped down through the slot A².

I will first describe the means for feeding

forward the strip of paper. E E' designate 70 rollers, between which the printed strip of paper passes and by the rotation of which said strip is fed along. The roller E' is mounted on the upper end of a shaft F, which shaft is journaled in suitable bearings formed upon the main frame of the machine. The roller E is mounted upon a stub-shaft F', 75 also journaled in a suitable bearing upon a portion of the main frame of the machine. Said bearing is somewhat slotted, as shown in dotted lines in Fig. 1, so that the shaft F may have a slight lateral play in its bearings. 80 This is for the purpose of permitting the roller E to yield slightly, if for any purpose it should be necessary for it so to do. The said roller E, it will be observed, comprises two cylindrical portions, between which is arranged a 85 fork e, extending from the frame of the machine. A coil-spring e', arranged between the jaws of said fork and bearing against a bearing-piece e² for the shaft F, tends to force said shaft, and consequently the roller E, constantly toward the roller E'. The spring e', 90 however, admits of the yielding of the roller E, as previously stated.

Upon the shaft F is a gear-wheel f, which gear-wheel meshes with a gear-wheel f', 95 mounted upon the shaft F'. When the shaft F is rotated, a corresponding rotary motion will be imparted to the shaft F', and the rollers E E' will consequently rotate in unison. Loosely mounted upon the shaft F is a gear-wheel f², with which engages a rocking gear-segment F². A pawl f³, mounted upon an arm f⁴, rigidly secured upon the gear-wheel f², engages a ratchet-wheel f⁵, rigidly mounted upon the shaft F. When the gear-wheel f² is rotated in one direction by the gear-segment F², the pawl f³ will play freely over the teeth upon the ratchet-wheel f⁵; but when 100 said gear-wheel is rotated in the opposite direction the pawl will engage the teeth upon the ratchet-wheel, and thus cause the rotation of the shaft F, and consequently of the rollers E E'. It is this motion which feeds the paper forward, and it occurs, as previously 105 stated, when the handle D² is being moved backwardly to its normal position. The gear-segment F² forms part of an arm g, which arm is rigidly secured near one of its ends upon a rock-shaft G, journaled in a bar upon the portion d of the frame, as shown more 110 clearly in Fig. 2. When the rock-shaft G is 115 rocked, a swinging motion will be given to the gear-segment F², which will cause the operation of the gear-wheel f², as previously described. Such rocking motion is imparted to the shaft G by means of a lever G', which, as 120 shown, is bent or curved around near one end. This bent or curved around portion bears near its outer extremity a roller g'. The roller g' is adapted to be operated upon by a four- 125 armed cam G². (Shown more clearly in Fig. 3.) This cam is loosely mounted upon the shaft D', and has secured to it upon one side a ratchet-wheel g². Rigidly mounted upon

the shaft D' is an arm g³, bearing a spring-actuated pawl g⁴, which pawl engages the teeth upon the ratchet-wheel g². When the handle D² is swung in the direction of the arrow, Fig. 3, the pawl g⁴ will slip freely over the teeth upon the ratchet-wheel g², and no rotary motion will be imparted to the cam G². Any tendency to such rotary motion is overcome by a stop-pawl g⁵, which is spring-actuated and abuts near its outer extremity against one of the arms of the cam G². The cam, however, when rotated in the other direction will strike said pawl g⁵ and lift it, so that one of said arms may pass beyond the pawl or into the position shown more clearly in Fig. 3. When the handle D² is swung in the other direction, the pawl g⁴ will engage the ratchet-wheel g² and cause the rotation of it and the cam G². The arm upon said cam, which is in contact with the roller g' upon the lever G', will then pass along said roller, and will cause the rocking of the lever G' and also the shaft G. Such rocking will cause the swinging of the gear-segment F².

I will now describe means whereby the check, after the same has been printed from, may be removed from beneath the chute A², in order to make room for the introduction of another check. To the other arm of the lever G' is pivotally connected one end of a link G³. The link G³ is pivotally connected near its other end to an arm h, extending from a movable piece H. The movable piece H is flat and of substantially the same thickness and height as is the check. The movable piece H is arranged to slide in a groove h' in the portion A³ of the frame, through which groove also pass the strip of paper and the inking-ribbon. This groove also receives the check when the latter is dropped down through the chute. A similar groove or passage-way is formed in the lower portion of the casing A', into which the upper part of the check extends. Near one end of the groove h' and in the lower side thereof there is an opening h², communicating with a passage-way h³. When the movable piece H is moved in the direction of the arrow, Fig. 1, the check will be moved along until above the passage-way h³, down which it will then fall, to be received in a suitable receptacle. (Not shown in the drawings.) The movement of the movable piece H to accomplish this is occasioned by the rocking of the lever G' during the return-movement of the handle D², as previously described.

I have shown a spring I, secured near one end to one arm of the lever G' and near the other end to the case A of the machine, which spring operates to retract the lever G' to its normal position, or the position shown more clearly in Fig. 3, and also to restore the movable piece H and the gear-segment F² to their normal position.

I have shown the slip of paper B as coiled upon a roller J. After leaving the roller J it passes over an idler-roller j, thence through

the groove h' over another idler-roller j', thence downwardly between the feed-rollers E E', and thence onto a roller J', upon which it is wound. Rotary motion is imparted to the roller J', so as to take up the strip by means of a belt j², passing about the hub of the cam G² and about a pulley j³, mounted upon the roller J'. When the diameter of the roll of paper upon the roller J' increases, the belt j² will slip, so that only a certain quantity of paper will always be fed forward. The strip of paper is gripped sufficiently tight between the rollers E E' to admit this slipping of the belt.

Although I have shown an inking-ribbon for causing the impression to be taken from the type, any suitable means might be employed for inking said type.

In practical operation it is advantageous that when the operation of the machine is commenced—as, for instance, in the morning—the cashier or person having it in charge should cause his name or some other sign to be printed upon the slip of paper. This should also be done when the use of the machine is discontinued—as, for instance, at night. In Fig. 4 I have shown a check adapted to do this. By this means it is always easy to ascertain where the recording for the day begins and ends upon the strip. It is to be observed that but one check at a time can be in position for printing, as a check when in the machine closes the lower end of the chute A², thus preventing the introduction of another check. When the check is being moved along by the movable piece H, the latter operates to close the lower end of the chute A², and another check cannot be introduced until after the movable piece H has been retracted to its normal position.

What I claim as my invention, and desire to secure by Letters Patent, is—

1. In a check-recording machine, the combination of a case provided with an opening through which a check may be passed, a stop for said check, a traveling strip of paper, inking apparatus, and a platen for causing an impression to be made upon the strip of paper from type upon the check, substantially as specified.

2. In a check-recording machine, the combination of a case provided with an opening through which a check may be passed, a stop for said check, a traveling strip of paper, inking apparatus, a platen for causing an impression to be made upon the strip of paper from type upon the check, a handle extending to the exterior of the case for operating said platen, and feeding mechanism for feeding said strip of paper along, substantially as specified.

3. In a check-recording machine, the combination of a case provided with an opening through which a check may be passed, a stop for said check, a traveling strip of paper, inking apparatus, a platen for causing an impression to be made upon the strip of paper

from type upon the check, a handle extending to the exterior of the case and operating said platen, feeding mechanism for feeding said strip of paper along, and a movable piece 5 for moving the check out of printing position after it has been printed from, substantially as specified.

4. In a check-recording machine, the combination of a case provided with an opening through which a check may be passed, a stop for said check, a traveling strip of paper, inking apparatus, a platen for causing an impression to be made upon the strip of paper from type upon the check, a handle extend-

ing to the exterior of the case, feeding mechanism for feeding the strip of paper along, and a movable piece for moving the check out of printing position after it has been printed from, said handle when moved in one direction operating the said platen and when 15 moved in the other direction operating said feeding mechanism and the movable piece, substantially as specified. 20

CHARLES ZALLUD.
